UNITED STATES PATENT OFFICE

EDWARD C. HOFFMANN, OF BEAVER DAM, WISCONSIN

COOKING STOVE OR RANGE

Application filed December 21, 1928. Serial No. 327,538.

This invention relates to cooking stoves or ranges.

An object of the invention is to provide an improved cooking stove including a number of doors capable of being adjusted about the stove to form an enclosing cabinet and mounted in such a way that they may be moved out of the way to positions to permit the stove to be used for its usual and intended purpose.

Another object of the invention is to provide an improved stove embodying any portion or all of the useful features herein disclosed, reference being made to the drawings 15 in which:

Fig. 1 is a perspective of my improved stove showing the doors or walls folded about the same to form a cabinet.

Fig. 2 is a similar perspective view showing the stove ready for use for its intended purpose, the folding doors or walls being in their open positions.

Fig. 3 is a horizontal sectional view just below the top wall of the oven showing the 25 mountings for the doors which are used to form enclosing walls.

Fig. 4 is a similar horizontal sectional view in a plane just below the lower wall of the upper oven and below the exposed burners.

Fig. 5 is a vertical front to rear sectional view showing the flexible top wall and the side walls thereof.

Fig. 6 is an enlarged sectional view showing the connections for controlling the flexible 35 top wall.

Fig. 7 is a front elevation of the lower left hand portion of the stove, the door and its guides being in section.

Fig. 8 is an enlarged vertical sectional view of the lower left hand portion of the 40 stove.

The present invention is embodied in a stove comprising the usual exposed burners 1 and grids 2 arranged in front of a rear wall 3, and at the side of a splash or oven wall 4, which latter forms one of the walls of the upper oven to which access is obtained through a door 5. The lower portion of the stove comprises an appropriately constructed 45 frame 6 above which and below the burners

1 and the oven 5 are a number of compartments to which access may be obtained by opening the closures 7 therefor.

The wall 4 has near its upper end a horizontal slot 8 through which projects the axle 55 9 of a pinion 10. The pinion 10 operates upon a rack 11 enclosed and supported by a channel portion 12 which may be provided by bending the top wall 13 of the oven 5 (Fig. 6). The outer end of the axle 9 is 60 connected with a bracket 14 attached to a plate 15^a, the rear edge of which is connected with the front portion of a flexible wall member 15. The inner edges of the plate 15^a and the wall member 15 operate adjacent to 65 the wall 4 and the opposite edges operate in a guide formed by flanges 16 projecting from a side bracket 17 attached to the right hand side of the stove (Fig. 2). The flexible wall 15 extends behind the upper end of the rear wall 3 and, in the construction shown, in front of a wall 18 rising vertically from the rear side of the stove a slight distance to the rear of the wall 3 and leaving a space 19 to receive the flexible wall 15 when said wall is moved 70 to the rear to open the stove for use. The wall 18 may be omitted, if desired. A link 20 has one end pivoted to a lug 21 projecting from the bracket 17 and the opposite end pivoted to one end of a link 22, the other end of 75 said link 22 being pivoted to the front portion of the plate 15^a adjacent to the outer end of said plate 15^a. This provides a support for the outer end of the front portion of the wall 15^a when said wall is drawn forwardly 80 beyond the front edge of the bracket 17.

Below the burners 1 and to the right of the compartment 7 an enclosed space is formed by an inner vertical wall 23, an outer vertical wall 24 and a front wall 25, said front wall 25 having therein a vertical opening 26. A pair of horizontal rods or shafts 27 are mounted in the space between the walls 23 and 24 and a bracket 28 is mounted for sliding movements on each of said rods or shafts. 95 A door 29 has its upper and lower ends pivoted to the brackets 28 and is movable into and out of the space between the walls 23 and 24 by sliding the brackets 28 along the rods 27. The upper and lower edges of the 100

door 29 are guided by bars 30 extending from front to rear between the walls 24 opposite the opening 26. The door 29 may be drawn through the opening 26 entirely out of the confined space between the walls 23 and 24 and folded around in front of the adjacent compartments 7, as shown in Fig. 1. Or, the door 29 may be moved into the space between the walls 23 and 24 leaving free access to the front of that portion of the stove which is covered or enclosed by said door 29.

The left hand side of the stove also includes a confined space between an inner wall 31 and an outer wall 32 and a front wall 33 having therein a vertical opening 34. In the lower portion of this confined space two parallel rods 35 are supported and a sliding bracket 36 is mounted on each of said rods. A door 37 has its upper and lower ends pivoted to the brackets 36 and is operative in like manner as the door 29 so that when withdrawn and folded toward the door 29 the free vertical edges of said doors 29 and 37 are adjacent to each other. The door 37 may be moved entirely into the space between the walls 31 and 32, the upper and lower edges of said door being operated between guides 38.

In the upper portion of the space between the walls 31 and 32 a door 39 is mounted in the same manner as the door 37 said door 39 having its upper and lower edges pivoted to brackets 40 operating on rods 40^a similar to the rods 35. This door 39 operates between guides 40^b like the guides 38. When the door 39 is withdrawn it encloses the front of the upper oven 5 and extends about to the plane of the wall 4. The doors 37 and 39 are separated by a facing strip 41 which extends the entire length of the front of the stove said strip bordering the upper ends of the doors 29 and 37 and the lower end of the door 39.

A confined space is formed to the rear of the wall 3 by an end wall 42 and a rear wall 43 and in said space a pair of horizontal rods 44 are mounted. Each of the rods 44 supports a bracket 45 which brackets are capable of sliding movements along the rods 44 and have their ends pivoted to the upper and lower ends of a door 46 which is capable of being withdrawn from the space in front of the rear wall 43 and folded around against the bracket 17. When this door 46 is folded around against the bracket 17 it forms a closure or wall for the upper right hand portion of the stove, as shown in Fig. 1. A supplemental door 47 is pivoted to the front edge of the door 46 by double hinges 48 which permit said door 47 to be folded to the position indicated by dotted lines in Fig. 3 in which the outer side of the door 47 is against the outer side of the door 46; or, the door 47 may be folded around to the front of the stove so as to cooperate with the door 46 and

the wall 15 to form an enclosure for the space above the burners 1. When the door 47 is extended around to the front its free vertical edge is adjacent to the free vertical edge of the door 39 and is above the facing strip 41 while the lower edge of the door 46 is above a rearward extension 49 of the facing strip. Thus, the door 47 may be folded rearwardly from the position shown in Fig. 1 so as to lie against the outer side of the door 46 and the door 46 may then be swung outwardly and moved inwardly into the confined space in front of the rear wall 43. The opening through which the doors 46 and 47 are moved into and from the confined space in front of the wall 43 may be closed by a door 50 having its rear edge hinged to the wall 43.

A latch device comprising an angular bracket 51 has one end hinged to the inner front edge of the door 46. When the door 47 is folded rearwardly against the outer side of the door 46 this latch bracket 51 may be swung around to enclose the front edges of the doors 46 and 47 and latched to the latter by a spring latch 52 of any appropriate construction.

From the foregoing it will be apparent that when it is desired to enclose the stove so as to obtain a cabinet device it is only necessary to withdraw the doors 29 and 37 and fold them to the front of the stove and also to withdraw the doors 39, 46 and 47 and fold them about the upper end of the stove in the obvious manner. Preferably, the flexible wall 15 is drawn forwardly before the walls 46 and 47 are folded about the upper end of the stove. When it is desired to open the cabinet thus obtained so as to use the stove for its intended purpose the doors may be opened and moved out of the way into their respective enclosures in the manner described.

I am aware that the construction, arrangement and relationship of the parts may be widely varied without departure from the nature and principle of the invention. I do not restrict myself unessentially, but what I claim and desire to secure by Letters Patent is:—

1. A stove comprising a series of burners, a fixed vertical wall at each of two sides of said burners, a flexible wall, means for supporting said flexible wall for sliding movements to position above said burners and to position rearwardly of the plane of certain of said burners, a horizontal rack, and a rotary pinion in connection with one edge of said flexible wall meshing with said rack.

2. A stove comprising a series of burners, a fixed vertical wall at each of two sides of said burners, a flexible wall, means for supporting one edge of said flexible wall for sliding movements by said flexible wall to position above said burners and to position rearward-

- ly of the plane of certain of said burners, a gear device for supporting and guiding the opposite edge of said flexible wall and a pair of hinged wall elements movable to positions in which one of said elements is at the side edge of said flexible wall and the other of said elements is at the front of said flexible wall. 5
3. A stove comprising a series of burners, a fixed vertical wall at each of two sides of said burners, a flexible wall, means for supporting said flexible wall for sliding movements to position above said burners and to position rearwardly of the plane of certain of said burners, a pair of hinged wall elements movable to positions in which one of said elements is at the side edge of said flexible wall and the other of said elements is at the front of said flexible wall, an enclosure for receiving said wall elements, and means supporting said wall elements for movement into and out of said enclosure. 10
4. A stove comprising an oven, and a number of burners at one side of said oven, in combination with a series of wall elements, and means for supporting said wall elements for sliding and pivotal movements to positions to enclose the front of said oven and to enclose the space at the front and at the side of said burners. 25
5. A stove comprising an oven, and a number of burners at one side of said oven, in combination with a series of wall elements, means for supporting said wall elements for sliding and pivotal movements to positions to enclose the front of said oven and to enclose the space at the front end at the side of said burners, and a sliding wall for closing the top of the space above the burners. 30
6. A stove comprising an oven, and a number of burners at one side of said oven, in combination with a series of wall elements, means for supporting said wall elements for sliding and pivotal movements to positions to enclose the front of said oven and to enclose the space at the front and at the side of said burners, and enclosures for receiving said wall elements when said wall elements are out of position to enclose said oven and said burners. 45
7. A stove comprising a series of compartments, a series of burners above one of said compartments, an oven at the side of said burners and above others of said compartments, and a series of swinging wall elements movable to position to enclose said oven and said burners and to position to expose said oven and said burners. 50
8. A stove comprising a series of compartments, a series of burners above one of said compartments, an oven at the side of said burners and above others of said compartments, a series of swinging wall elements movable to position to enclose said oven and said burners and to position to expose said oven and said burners. 60
9. A stove comprising a series of compartments, a series of burners above one of said compartments, an oven at the side of said burners above others of said compartments, an enclosure at one end of the stove below said burners, another enclosure at the opposite end of said stove from said first enclosure, supports mounted in said enclosures, brackets mounted for sliding movements on said supports, and a door supported by the brackets on each of said supports and being movable into said enclosures and from said enclosures and to position to enclose the front of said compartments. 70
10. A stove comprising a series of compartments, a series of burners above one of said compartments, an oven at the side of said burners above others of said compartments, an enclosure at one end of the stove below said burners, another enclosure at the opposite end of said stove from said first enclosure, supports mounted in said enclosure, brackets mounted for sliding movements on said supports, a door supported by the brackets on each of said supports and being movable into said enclosures and from said enclosures and to position to enclose the front of said compartments, and a series of doors for enclosing the front of said oven and the space above said burners. 75
11. A stove comprising a series of compartments, a series of burners above one of said compartments, an oven at the side of said burners above others of said compartments, an enclosure at one end of the stove below said burners, another enclosure at the opposite end of said stove from said first enclosure, supports mounted in said enclosure, brackets mounted for sliding movements on said supports, a door supported by the brackets on each of said supports and being movable into said enclosures and from said enclosures and to position to enclose the front of said compartments, a series of doors for enclosing the front of said oven and the space above said burners, and enclosures for receiving said doors when said doors are moved to positions to expose said oven and said burners. 80
12. In a stove, a series of burners, a pair of spaced walls at the rear of said burners, a wall at one side of said burners, a bracket at the opposite side of said burners, a flexible wall having one end supported by said bracket and being movable forwardly and rearwardly above said burners, and means for guiding said flexible wall. 100
13. In a stove, a series of burners, a pair of spaced walls at the rear of said burners, a wall at one side of said burners, a bracket at the opposite side of said burners, a flexible wall having one end supported by said bracket and being movable forwardly and rearwardly above said burners. 105
14. In a stove, a series of burners, a pair of spaced walls at the rear of said burners, a wall at one side of said burners, a bracket at the opposite side of said burners, a flexible wall having one end supported by said bracket and being movable forwardly and rearwardly above said burners. 110
15. In a stove, a series of burners, a pair of spaced walls at the rear of said burners, a wall at one side of said burners, a bracket at the opposite side of said burners, a flexible wall having one end supported by said bracket and being movable forwardly and rearwardly above said burners. 115
16. In a stove, a series of burners, a pair of spaced walls at the rear of said burners, a wall at one side of said burners, a bracket at the opposite side of said burners, a flexible wall having one end supported by said bracket and being movable forwardly and rearwardly above said burners. 120
17. In a stove, a series of burners, a pair of spaced walls at the rear of said burners, a wall at one side of said burners, a bracket at the opposite side of said burners, a flexible wall having one end supported by said bracket and being movable forwardly and rearwardly above said burners. 125
18. In a stove, a series of burners, a pair of spaced walls at the rear of said burners, a wall at one side of said burners, a bracket at the opposite side of said burners, a flexible wall having one end supported by said bracket and being movable forwardly and rearwardly above said burners. 130

wall having one end supported by said bracket and being movable forwardly and rearwardly above said burners, means for guiding said flexible wall, and means cooperating with said flexible wall to enclose the space above said burners.

14. In a stove, a series of burners, a pair of spaced walls at the rear of said burners, a wall at one side of said burners, a bracket at the opposite side of said burners, a flexible wall having one end supported by said bracket and being movable forwardly and rearwardly above said burners, means for guiding said flexible wall, a pair of hinged doors, and means for supporting said doors in position to cooperate with said flexible wall to enclose the space above said burners and permitting movement of said doors to position to expose the space above said burners.

15. In a stove, a series of burners, a pair of spaced walls at the rear of said burners, a wall at one side of said burners, a bracket at the opposite side of said burners, a flexible wall having one end supported by said bracket and being movable forwardly and rearwardly above said burners, means for guiding said flexible wall, a pair of hinged doors, and means for supporting said doors in position to cooperate with said flexible wall to enclose the space above said burners and permitting movement of said doors to position to expose the space above said burners, and walls forming an enclosure for receiving said doors when said doors are in position to expose the space above said burners.

16. In a stove, a pair of spaced walls, supports mounted in said walls, sliding brackets on said supports, door elements hinged to said brackets and movable into and out of the space between said walls, and a device for closing the end of the space between said walls.

17. A stove comprising a series of burners, a fixed wall at one lateral side of said burners, a fixed wall at the rear side of said burners, a pair of wall elements, hinged for supporting one of said wall elements by the other and hinges for supporting said other wall element for movement of said wall elements to positions at the sides of said burners opposite from said walls and for movement away from said burners, and a flexible wall for closing the space above said burners.

55 EDWARD C. HOFFMANN.
